UNITED STATES PATENT OFFICE.

JOEL HOWARD GARRETSON, OF FORSYTH, MONTANA.

FOLDING UMBRELLA.

1,297,140.

Specification of Letters Patent. Patented Mar. 11, 1919.

Application filed September 28, 1918. Serial No. 253,058.

To all whom it may concern:

Be it known that I, JOEL HOWARD GARRETSON, a citizen of the United States, residing at Forsyth, in the county of Rosebud and 5 State of Montana, have invented new and useful Improvements in Folding Umbrellas, of which the following is a specification.

This invention relates to improvements in umbrellas and aims to provide an umbrella 10 for use in the ordinary manner and which may be compactly folded and packed within a traveling bag or suit case.

Another object of the invention is to provide a novel form of folding rib, which, 15 when extended for use will be securely held in position against accidental folding.

A further object is the provision of a sectional telescopic handle or rod, which may be reduced to substantially the same length 20 as the ribs when the latter are folded.

Other objects and advantages of the invention will appear when the following description is read in connection with the accompanying drawings.

25 In the drawings:—

Figure 1 is a sectional view of an umbrella constructed in accordance with the present invention and shown in partly opened position;

30 Fig. 2 is a similar view of the umbrella folded the lower sections of the rod or handle being removed;

Fig. 3 is a sectional view of the lower end of the rod described within a handle;

35 Fig. 4 is an enlarged fragmentary view of a hinged connection between the ribs and stretchers, the ribs being shown extended or in position for use;

Fig. 5 is a similar view with the rib partly 40 folded;

Fig. 6 is an edge view of the connection as shown in Fig. 4;

Fig. 7 is an enlarged longitudinal sectional view on the line 7—7 of Fig. 1; and

45 Fig. 8 is a similar view on the line 8—8 of Fig. 1.

Referring to the drawings in detail, wherein like characters of reference denote corresponding parts, the umbrella is indicated at 10. This rod is of sectional formation and includes the outer section 11 and the inner section 12. These two sections are removably joined together through the medium of a reduced threaded extension 13 55 carried by the section 11, which engages a

threaded socket 14 formed in the adjacent end of the section 12.

The section 11 is provided with the usual annulus 15, to which are pivoted one end of ribs 16. These ribs are also formed in sections and comprise the inner section 17 and the outer section 18.

Pivots secured to an ear 19 carried by a sleeve 20, which is located adjacent one end of the section 17, are stretchers 21, these 65 stretchers being also pivotally connected to a sleeve 22 mounted for sliding movement upon the rod 10 in the usual manner. This sleeve is provided with a slot 23, which, when the umbrella is closed will engage over 70 a spring catch 24 and the umbrella when open for use, will engage over a spring catch 25, the catches 24 and 25 being of the ordinary or any preferred construction.

The rib sections 17 and 18 are hingedly 75 or pivotally secured together, the extremities of the sections 17 being formed with spaced parallel ears 26 and the adjacent ends of the section 18 are pivoted between these ears as shown at 27. The extremities of the sections 80 18 extend beyond the pivoted point and are adapted to be engaged by a sleeve 28 which is slidably and rotatably mounted upon the end of the sections 17. This sleeve is limited in its sliding movement by contact 85 with the sleeve 20 and with an inclined surface 29 formed on the ears 26. By sliding the sleeve in the direction of the ears, the former will engage the inclined surface 29 and be frictionally held in position. The 90 sleeves 28 are each provided with a notch 29' and when this notch is in register with the slot formed by the space between the ears 26, the section 18 may be folded. When in reverse position the sleeve may be jammed 95 upon the inclined surface 29, whereupon the said sleeve will be prevented from rotating, so that the notch will be held out of register with the slot and the ribs thus securely held in alined position.

When it is desired to open the umbrella for use, the rib sections are arranged as shown in Figs. 1 and 4, whereupon the umbrella may be opened in the usual manner. When it is desired to fold the umbrella for 105 packing, the ribs are folded in the manner shown in Fig. 2, with the sleeve 22 above the catch 25, the pivotal connection between the ribs and stretchers permitting of this position of the sleeve. The section 12 of the 110

rib 10 is then telescoped within the handle 30, which is hollow as shown at 31 for this purpose. The section 12 of the rib 10 is held in extended position through the 5 medium of a spring catch 32. This catch has pivoted within the section 12 as shown at 33, one end of the said catch projecting beyond the periphery of the rib section for engagement with the upper edge 34 of the 10 handle. The handle is provided with an extending sleeve 35, which is slotted as shown at 36. This sleeve acts as a guide for the section and aids in maintaining the section and guide in proper alinement, while 15 the slot 36 permits of the passage of the end of the latch, so that the latter may engage the upper edges 34 of the said handle.

The invention is susceptible of various changes in its form, proportions and minor 20 details of construction and the right is re-

served to make such changes as fall within the scope of the appended claim.

Having described the invention, what is claimed is:—

A folding umbrella comprising a sectional 25 rod, ribs of inner and outer sections hingedly secured to one of the rod sections, stretchers pivotally secured to said ribs, spaced ears located at the extremity of the inner sections of said ribs and spaced from 30 the hinged connection of the stretchers, said ears being provided with inclined wedge surfaces, means for hingedly connecting the outer rib section between said ears, and a sleeve slidably mounted between the hinged 35 connection of the stretchers and ears for frictional engagement over the ends of the outer rib sections.

In testimony whereof I affix my signature.

JOEL HOWARD GARRETSON.
